ABSTRACT: A flush top cooking unit wherein the heating element therefor has a broad heating surface which is disposed adjacent to but spaced from the underside of an exposed imperforate thermal conductive plate. Encircling the perimeter of the heating surface and in sealing engagement with the plate underside is an upright thermal shield. The plate underside and the thermal shield cooperate with the heating surface to form a broad but shallow passageway through which air circulates and scrubs the plate underside.

FLUSH TOP COOKING UNIT WITH VENTILATING MEANS

BACKGROUND OF THE INVENTION

Various flush top cooking units have heretofore been proposed which are adapted primarily for domestic type cooking. Such units, however, because of certain design characteristics, have been beset with numerous shortcomings. For example, because of the high localized concentration of heat at various areas of the exposed flush top plate, the plate becomes highly susceptible to breakage. Secondly, a substantial "cool down" period is often required for the top plate subsequent to the heater or heating means being deactivated. Furthermore, because of the heat retention characteristics of the top plate utilized in said prior units, undesirable "overshooting" of the prescribed cooking temperature frequently occurs which adversely affects the palatable nature of the food being cooked. Lastly, installation, maintenance and servicing costs associated with prior units are oftentimes inordinately high.

SUMMARY OF THE INVENTION

Thus, it is an object of this invention to provide a flush top cooking unit which avoids the aforesaid shortcomings of the prior units.

It is a further object of this invention to provide a flush top cooking unit which has a pleasing esthetic appearance and may be readily installed in counter tops, standing ranges, slip-in ranges, etc.

It is a further object of this invention to provide a flush top cooking unit wherein the controls therefor are completely recessed from the exposed top surface, are readily accessible for manipulation, when desired, and when not in use may be concealed from view.

It is a still further object of this invention to provide a flush top cooking unit wherein the heating means therefor are shielded and protected against any soiling or damage caused by spilling liquids, food, or other foreign particles on the exposed top surface.

It is a still further object of this invention to provide a flush top cooking unit, wherein the exposed top surface thereof is free of any projections or obstructions which might interfere with the use of the top surface for cooking or for use as a counter top or work area.

It is a still further object of this invention to provide a flush top cooking unit wherein the top plate which overlies the heating means has the portion of the underside thereof in registration with the heating means subjected to continuous scrubbing by circulating air thereby permitting an intense flow of infrared radiation to pass through the top plate while holding the conductive heat levels within the limits of the top plate.

Further and additional objects will appear from the description, accompanying drawings and appended claims.

In accordance with one embodiment of the invention, a flush top cooking unit is provided which is adapted to be installed within a suitable opening formed in a substantially flat supporting surface. The unit includes a heating means having a broad upper heating surface and a heat conductive imperforate top panel having the underside thereof overlying, in closely spaced relation, the said heating surface so as to form a shallow passageway. The heating surface is delimited by a plurality of inlet ports and is provided with a discharge port spaced inwardly from the perimeter of said surface. Both the inlet and discharge ports communicate with the passageway. Encompassing the heating surface and the inlet ports is an upstanding thermal shield which sealingly engages the underside of the top panel. Blower means is provided which is in communication with the discharge port and thereby causes air to be circulated through the passageway and scrub the top panel underside.

For a more complete understanding of the invention, reference should be made to the drawings wherein:

FIG. 1 is a fragmentary perspective top view of one form of the cooking unit shown mounted on a flat supporting surface and with the manual controls therefor concealed from view;

FIG. 2 is similar to FIG. 1 but showing the manual controls exposed;

FIG. 3 is a fragmentary perspective exploded top view of the cooking unit shown in FIG. 1;

FIG. 4 is similar to FIG. 2 but with the imperforate top panels removed so as to show the relative positioning of the heating means, the controls therefor, and the blower housing;

FIG. 5 is a fragmentary sectional view taken along line 5-5 of FIG. 2;

FIG. 6 is a fragmentary sectional view taken along line 6-6 of FIG. 2;

FIG. 7 is a fragmentary sectional view taken along line 7-7 of FIG. 1;

FIG. 8 is a schematic wiring diagram for the manual controls shown in FIG. 4;

FIG. 9 is an enlarged fragmentary vertical sectional view of one form of heating means; and

FIG. 10 is an enlarged fragmentary vertical sectional view through one form of collector chamber and showing the bottom of the chamber gasketed from the bottom of the inner housing.

DESCRIPTION

Referring now to the drawings and more particularly to FIGS. 1 and 2, a flush top cooking unit 10 is shown mounted within a suitable opening 11, see FIG. 4, formed within a substantially flat supporting surface 12. The supporting surface 12 may be a kitchen counter, top surface of a standing range, or the like.

The unit 10 in the illustrated embodiment includes an outer, open top housing 13, see FIG. 3, formed from suitable sheet metal material. The housing 13 is provided with a bottom panel 14 which is delimited by upstanding sidewalls 15. The bottom panel 14 or opposed sidewalls may be provided with a plurality of small openings 16 disposed in the marginal portion of panel 14, see FIG. 3, or along the bottom edges of the sidewalls 15, not shown. The function of these openings will be discussed more fully hereinafter. The outside dimension and configuration of the outer housing 13 closely approximate the perimeter of the opening 11 formed in the supporting surface 12.

Disposed within the outer housing 13 is an inner, open top housing 17, which is also formed from suitable sheet metal material. Housing 17 includes a bottom panel 18 and upstanding sidewalls 20 which terminate at their upper edges in outwardly projecting flanges 21. The sidewalls 20 are preferably provided with a lamina 19 of thermal insulative material, see FIGS. 5 and 7. The flanges 21 may, if desired, be secured by any suitable means to the corresponding sidewalls 15 of the outer housing 13.

The respective dimensions of the inner and outer housings are such that the bottoms are spaced relative to one another as is the case with the respective sidewalls. Thus, a spacing 22 is formed between the housings. The portion of the spacing 22 between the bottom panels 14 and 18 is preferably filled with suitable thermal insulating material 23. The remainder of the spacing 22, on the other hand, is open so that air may circulate therethrough in a manner to be hereinafter described.

Positioned within the inner housing 17 are a plurality of heaters or heating means 24 which are electrically energized. The heaters 24 in the illustrated embodiment are arranged in two spaced rows of two heaters each and each row extends from front to rear. Thus, there are two front (RF & LF) and two rear (RR & LR) heaters or sometimes referred to as burners, see FIG. 4. Each heater is of like construction and in the illustrated embodiment comprises a ceramic plate 25 having a broad upper heating surface 26, see FIG. 9. Embedded in surface 26 is a high resistance wire 27. The center of the plate 25 is provided with an enlarged opening 28, see FIGS. 3, 5, 6 and 75 9.

Each heater of a row rests upon a ceramic base panel 30. Because of the arrangement of the rows there are two base panels 30. Each panel 30 is provided with a plurality of inlet ports 31 which are arranged in such a way as to delimit the heating surface 26 of a heater, see FIGS. 4 and 9. The ports 31, in turn, are delimited by a ringlike thermal shield 32 which extends upwardly from the panel 30. The shield 32, as illustrated in FIG. 9, includes a metallic bracket 32a to the top of which is affixed a gasket 32b of thermal insulative material.

Overlying the broad surface 26 of the heater 24 and in spaced relation with respect thereto is an imperforate plate 33 of thermal conductive material (e.g., glass). In the illustrated embodiment, two plates 33 are provided, one for each row of heaters 24. The plate 33, in addition to being imperforate, must be inflexible, strong, and shock-resistant, even when subjected to high temperature (e.g., 1500° F.); and, in addition, must be attractive in appearance and capable of being readily cleaned with a damp cloth or the like. The underside of plate 33 is in sealing engagement with the shield gasket 32b, see FIG. 9. Thus, by reason of the relative positioning of the heater surface 26, the underside of plate 30, the thermal shield 32 with respect to the perimeter of the ceramic plate 25, and the plurality of ports 31, a broad shallow passageway 34 is formed through which air is circulated, see directional arrows in FIG. 9, in a manner to be described more fully hereinafter.

Disposed beneath base panel 30 and in registered relation therewith is a collector chamber 35, which may also be formed of suitable sheet metal material. The bottom of the chamber 35 may, if desired, be formed by the bottom 18 of the inner housing 17, see FIGS. 5-7, or may be a separate panel 35a which is spaced from the bottom 18 of the inner housing 17 and separated therefrom by a suitable thermal insulative gasket 29, see FIG. 10. The underside of chamber 35 is provided with a pair of spaced inlet ports 36a and 36b, see FIG. 7, each being vertically aligned with the opening 28 formed in a corresponding heater 24. Normally the top of the collector chamber 35 is disposed approximately one inch (1") beneath panel 30. A pipe connection 37, may be utilized to connect the heater opening 28 with the respective port 36a or 36b of the collector chamber 35, see FIGS. 5, 7 and 9.

The sidewalls 20 and bottom 18 of the inner housing 17, the respective base plate 30 and upper portion of the collector chamber 35, all cooperate with one another to form a cavity 38. One side of the cavity is formed by a partition 40 which extends from the bottom 18 of the inner housing 17 to a frame member 41 which overlies the marginal portion of the imperforate top plate 33. The frame member 41 will be described more fully hereinafter.

The partitions 40, which cooperate with the respective row of heaters, are in spaced substantially parallel relation with respect to one another and define the sidewalls of an elongated well 42. Well 42 separates the rows of heaters and accommodates a control assembly 43 and a blower unit 44.

Formed in each partition 40 and substantially centrally thereof is an elongated opening 45 which interconnects the well 42 with the adjacent cavity 38. Thus, ambient air is supplied to each cavity from the well 42.

Overlying the well 42 is an imperforate plate 46 which is held by a central portion 41a of the frame 41. Disposed rearwardly of plate 46 is an exhaust port 47 for the blower unit 44. Disposed within the port 47 is a louver 48, see FIG. 3, which may be adjustable, if desired, to control the direction of flow of the exhaust air from the blower unit to the outside of the cooking unit. The exposed surfaces of plates 33 and 46 are in substantially coplanar or flush relation with respect to the exposed supporting surface 12.

Mounted forwardly of plate 46 is an opening 50 which communicates with the well 42. The opening 50 is in registered relation with the control assembly 43, the latter being disposed within the well and at the forward end thereof so as to be readily accessible for manual adjustment. Slidably mounted on the underside of the portion of the frame circumjacent the opening 50 is a cover 51. The cover is capable of being manually adjusted to its retracted or fully open position

A, as seen in FIG. 2, or its fully closed or forward position B, as seen in FIG. 1. When the cover 51 is in position B, it is in substantially coplanar relation with respect to plate 46 and conceals the whole control assembly 43 from view and protects same from liquid, food or foreign particles.

On the other hand, when cover 51 is in position A, the control assembly 43 is exposed and a switch 52, see FIG. 8, is actuated thereby causing the blower unit 44 to become automatically actuated. The switch 52, see FIG. 6, is mounted on the underside of the frame central portion 41a and in the path of movement of the cover 51, when it reaches its fully opened position. The circuit diagram shown in FIG. 8 will be described more fully hereinafter.

A conventional spring-loaded detent, not shown, may be provided to retain the cover 51 in its retracted position. To release the cover from its retracted position in such a case, would require only a slight downward pressure being exerted on the forward edge 51a of the cover 51.

The control assembly 43 in the illustrated embodiment includes a plurality of heat selector switches 53, 54, 55 and 56; one heat selector switch being provided for each heater 24. The switches 53-56 are arranged in a clustered relation on a bracket 57, see FIGS. 4-6. The bracket 57 is secured to the bottom 18 of the inner housing 17 which forms a part of the well 42. The surface 57a of the bracket on which the switches 53-56 are mounted is elevated with respect to the bottom surface 18. The front and rear sides of the bracket are open so that air may be readily circulated beneath surface 57a, when the blower unit is actuated, and thus provide a cooling effect upon the switches 53-56.

Each switch 53-56 may be of a conventional bimetal time relay type wherein when the knob thereof is rotated from its "off" position, current begins to flow through the resistance wire 27. The period of time the current will flow through the wire 27 will be determined by the setting of the knob which in turn will vary what effect the warpage of the bimetal element will have on making and breaking the circuit contact.

Disposed within well 42 and behind bracket 57 is a mixing chamber 58, see FIG. 6, which is in communication with the discharge opening 60, see FIG. 7, of each collector chamber 35. The rear end of mixing chamber 58 is provided with a discharge port 61, over which is positioned a cowl or hood 62. The cowl 62, in turn, is connected to the suction side of the blower unit 44.

The blower unit, which is positioned within the well 42 and at the rear thereof, includes a housing 63 in which is disposed the blower impeller, not shown. One side of the blower housing is open and in registration with a side of the cowl 62. In addition to the open side, the housing has a second intake opening 63a formed in the end wall, see FIG. 3. Opening 63a is in communication with the spacing 22 formed between the outer and inner housings 13 and 17. Circulation of ambient air within spacing 22 is effected by reason of the inlet ports 16, see FIG. 3, and the opening 63a of the blower housing. The top wall of the housing 63 is provided with a discharge port 63b, which in turn is in registration with opening 47 formed in the frame central portion 41a.

The blower unit motor 64 is mounted on the end of the housing 63 opposite opening 63a and within spacing 22. There is provided on the end of the blower unit housing 63, on which the motor 64 is mounted, one or more openings, not shown, which are connected to the suction side of the blower thereby assuring that ambient air circulates past the motor 64 and cools same.

As seen in FIG. 8, switch 52, which is normally open and is actuated into a closed position by retracting cover 51, causes blower 64 to be actuated whereupon a magnetic switch 65, or 70 a vane type switch if desired, which is biased by a spring or the like to a normally open position, is moved to a closed position thereby causing the individual heat selector switches 53-56 to be electrically alive. Each of the selector switches is of like construction and is provided with a knob which is capable of being manually adjusted to various selected positions. As

previously noted, each of said switches is of conventional design and may be a bimetal type, if desired.

As seen in FIG. 8, the line voltage is preferably 240 v. with a center ground wire. The blower 64 and switch 52 are connected in series and across only one-half the line voltage (i.e., 110 v.). Once the blower 64 is actuated, magnetic switch 65 is closed. It should be noted that when switch 65 is closed, the full line voltage (220 v.) is available for selector switch 56. The remaining selector switches 53-55 are arranged in parallel connection with each other as well as switch 56 by appropriate wiring 57a-b. Each of the selector switches is adjustable independently of the other and is connected in series with the corresponding resistance wire 27.

When any of the heaters 24 are actuated by manipulation of the respective selector switch, the blower 44 will already be operating whereby ambient air will be circulated within space 34 as indicated by the flow arrows shown in FIG. 9. This circulation will provide a scrubbing effect on the underside of the imperforate panel 33. This scrubbing effect is important because (a) it permits the utilization of full heat application beneath panel 33 without exceeding the temperature limits of the panel; (b) it accelerates cool down of the exposed surface of the panel 33, provided the cover 51 remains in its retracted position A; (c) it provides a quicker reaction to the "turn down" requirements as dictated by the selector switch knob, by reducing the heat retention characteristics of the panel 33; and (d) it controls the "overshoot" characteristic of the heater by quickly pulling heat from a given mass area. The "overshoot" characteristic is a condition, which often occurs in prior electrical cooking devices, wherein the desired cooking temperature is exceeded even though the heater is turned off. This condition is caused by the heat retention properties of the electrical elements and other surrounding mass.

As aforescribed, the actuation of the blower 44 causes a constant flow of ambient air past the control or selector switches thereby preventing overheating of the same. There is also a continuous air circulation in the spacing 22 between the outer and inner housings thereby keeping the sides of the outer housing relatively cool so as to not overheat or adversely affect the structural supporting members surrounding the unit 10.

Thus, it will be seen that a flush top cooking unit has been provided which is simple to install, permits accurate control of the individual heaters, protects the heaters against spilled liquids, food or other foreign particles, and permits the working or cooking area to be free of any undesirable protuberances. In addition, the cooking unit permits an intense flow of infrared radiation from the individual heaters to pass through the portions of the imperforate top plate overlying same without exceeding the limits of conductive heat of the top plate.

While several embodiments of the invention have heretofore been described, it is to be understood, of course, that the invention is not limited thereto, but further modifications are contemplated and it is intended by the appended claims to cover such modifications.

I claim:

1. A cooking unit for mounting within an opening formed in a substantially flat supporting surface, said unit comprising a first housing positionable within the surface opening, said housing having a bottom delimited by upstanding sidewalls; a second housing disposed within and supported by said first housing, said second housing having a bottom delimited by upstanding sidewalls, the bottoms and respective sidewalls of said housings being in relatively spaced relation; electrical heating means disposed within said second housing, said heating means having a broad upper heating surface provided with an exhaust port spaced a substantial distance from the perimeter of said heating surface, said heating surface being delimited by a plurality of inlet ports; a first plate of thermal insulating material for supporting said heating means, said plate overlying and being secured to said second housing; a thermal shield extending upwardly from said first plate and en-

circling the plurality of inlet ports delimiting said heating surface; an air collecting chamber disposed within said second housing and positioned beneath said heating means, said chamber having an input port connected to the exhaust port of said heating means and a discharge port spaced from said input port; an imperforate second plate formed of thermal conductive material overlying said housings and said heating means, said second plate having the upper exposed surface thereof positionable in substantial flush relation with respect to the portion of the supporting surface circumjacent the opening formed therein, the underside of said second plate being in sealing engagement with said thermal shield and disposed in spaced relation with respect to said heating surface so as to form a passageway through which air is circulated to effect uniform heating of the upper exposed surface of said second plate in registration with said broad upper heating surface of said heating means, said passageway communicating with the interior of said second housing through said plurality of inlet ports delimiting said heating surface and communicating with said collecting chamber through said exhaust port formed in said heating means; blower means having the suction side thereof communicating with the discharge port formed in said collecting chamber, the discharge side of said blower means exhausting outside said first housing; and control means operatively connected to said blower means and said heating means for actuating same.

2. The cooking unit of claim 1 wherein said control means is disposed within the interior of said second housing and is recessed with respect to the exposed surface of said second plate.

3. The cooking unit of claim 2 including an adjustably mounted cover for said recessed control means, said cover means being adjustable to open and closed positions; said cover, when in said closed position, concealing said control means and having the exposed surface thereof disposed in substantially flush relation with respect to the exposed surface of said second plate.

4. The cooking unit of claim 3 including switch means connected to said blower means and said control means and operative by said cover when the latter is adjusted to said open position whereby said blower means is automatically actuated.

5. The cooking unit of claim 1 whereby the bottom of said first housing is perforated and the suction side of said blower means is also in communication with the spacing formed between said housings.

6. The cooking unit of claim 1 whereby the sidewalls of said second housing are thermally insulated.

7. The cooking unit of claim 6 including gasketing means disposed between said collecting chamber and the bottom of said second housing.

8. The cooking unit of claim 1 including additional heating means of like construction, all of said heating means being arranged in at least two parallel spaced rows, the control means for said heating means being recessed within said second housing and beneath the exposed surface of said second plate and disposed intermediate a pair of spaced rows.

9. The cooking unit of claim 8 including an adjustable cover mounted adjacent said recessed control means, said cover, when in a first position of adjustment, overlying and concealing said control means and having the exposed surface of said cover substantially flush with the exposed surface of said second plate; said cover, when in a second position of adjustment, exposing said control means for manual manipulation of the latter and actuating said blower means whereby outside air is circulated by said blower means into contact with said control means and through said passageway beneath the underside of said second plate.

10. The cooking unit of claim 1 wherein said thermal shield delimits a plurality of ports arranged in encircling relation with respect to the perimeter of said heating surface; said heating surface is substantially air impervious except for a port disposed substantially centrally thereof, said ports being in communication with said passageway and said blower means.
